CLAIM

The ornamental design for a wireless dome camera, as shown and described.

DESCRIPTION

FIG. 1 is a perspective view of a wireless dome camera;
FIG. 2 is a left side elevational view thereof;
FIG. 3 is a right side elevational view thereof;
FIG. 4 is a front elevational view thereof;
FIG. 5 is a rear elevational view thereof;
FIG. 6 is a top plan view thereof; and,
FIG. 7 is a bottom plan view thereof.

The broken lines in the drawings are included for the purpose of illustrating environmental subject matter and form no part of the claimed design.
